UNITED STATES PATENT OFFICE.

MALCOLM L. COSSITT, OF ALAMEDA, CALIFORNIA, ASSIGNOR TO MANIFOLD IMPRESSIONS CORPORATION, OF CARSON CITY, NEVADA, A CORPORATION OF NEVADA.

MANIFOLDING ATTACHMENT FOR TYPEWRITERS

Application filed June 21, 1922. Serial No. 569,801.

To all whom it may concern:

Be it known that I, MALCOLM L. COSSITT, a citizen of the United States, residing at Alameda, in the county of Alameda and State of California, have invented certain new and useful Improvements in Manifolding Attachments for Typewriters, of which the following is a specification.

My invention relates to that class of manifolding attachments for typewriters in which one or more manifolding members are carried by arms mounted on the platen carriage of the machine, and are adapted, by the movement of said arms, to be placed in and removed from functional position in the line of type impact; and more especially it relates to a form of such attachments in which the arms are carried by a plurality of independently rotatable, nested sleeves, and the manifolding members are stored upon the attachment in such wise as to adapt them to be drawn out in successive lengths or sections for association with the arms, and presentation in the line of type impact.

The chief object of my present invention is to so combine the rotative nested sleeves, the stored manifolding members, and the ribbon carrying arms, as to produce a compact structure in which the nested members are kept down to practicable diameters, the storing housings and one set of arms being detachably fitted to one end of the nested sleeves whereby they may be removed readily and others substituted as occasion requires.

To this end, my invention consists in the novel manifolding attachment for typewriters which I shall now fully describe by reference to the accompanying drawings, in which—

Fig. 1 is a front elevation, partly broken, of my manifolding attachment.

Fig. 2 is a perspective view, enlarged, of the set of ribbon carrying arms at the right hand end.

Fig. 3 is a left hand end elevation showing the arms elevated.

Fig. 4 is an elevation of Fig. 3, showing the arms depressed to functional position.

Fig. 5 is a top plan, enlarged, broken, and partly in section of the left hand end of my attachment.

Fig. 6 is a section on the line 6—6 of Fig. 5.

Fig. 7 is a perspective view of one of the 55 left hand end arms.

Fig. 8 is a perspective view of one of the 60 storing housings for the manifolding ribbons, showing its detachable fitting to its carrying member.

Fig. 9 is a perspective detail of two of the 65 nested carrying members.

Fig. 10 is a detail view of the locking device for the nested members, taken on the line 10—10 of Fig. 6.

1 is the platen carriage of a typewriter and 2 is the platen. Secured upon the platen carriage, one near each end, are the brackets 3. In these brackets are journaled short shafts 3' with cranks 3".

Between the free extremities of the cranks 3" are carried the independently rotatable nested sleeves, the innermost, which may be a rod, as here shown, being designated by 4, the middle one by 4' and the outermost 75 by 4".

At the right hand end the sleeves carry the ribbon carrying arms 5, 5' and 5" respectively, Figs. 1 and 2, each arm having a stud 6 which may indicate means for the 80 manual or mechanical operation by which the arms are moved with the sleeves as axes to primarily carry their ribbons down towards functional position.

At the left hand end, the sleeves project 85 beyond their carrying bearing, to successively different distances, as seen clearly in Fig. 6, the innermost 4 extending the longest distance and the outermost 4" extending the shortest distance.

The innermost sleeve or rod 4 carries at its extremity a housing 7, within which is fitted a rotatable spool 8 upon which is wound a manifolding ribbon 9.

The middle sleeve 4' carries at its extremity a housing 7' with a rotatable spool 8' and a manifolding ribbon 9'.

In similar manner the outermost sleeve 4" has a housing 7" with a rotatable spool 8" and ribbon 9".

Each housing is detachably fitted to its sleeve to rotate therewith, by means of a spline 10 fitting in a groove 10'—Figs. 6, 8 and 9, and said housings are of successively diminished diameters. To the housings are 105 secured the ribbon carrying arms 11, 11' and 11" respectively, said arms extending in spaced relation over the housing series, and

provided with outwardly bent ends 12, in which are ribbon guiding slots 12'—Figs. 5 and 7.

Each housing has on its periphery an angular slot 13—Fig. 8, through which the manifolding ribbon emerges—Fig. 5. The ribbons thence extend along the arms 11, 11' and 11''—Figs. 5 and 6, and through the slots 12' in the ends 12 of said arms and thence to the arms 5, 5' and 5'' at the other ends of the sleeves, and through toothed slots 14 in said arms—Figs. 1 and 2.

In operation, as is the case with manifolding attachments of this general nature, the 15 ribbons are placed in and removed from functional position in the line of type impact, by swinging their carrying arms first with the sleeves as axes, and then upon the shafts 3' as an axis, as indicated in Figs. 3 20 and 4; and, as in forms of these attachments in which the ribbons are stored and are adapted to be drawn out in successive lengths to present fresh sections for use, as preceding ones are worn out, said ribbons are 25 released from the teeth of the slots 14 in the carrying arms at the right and are drawn out from their spools as needed and reengaged on said arms. But in the present construction, by carrying the spools on the 30 outside of the sleeves, these nested elements may be confined to practicable dimensions, and by carrying one set of ribbon arms on the spool assembly, it is possible to readily apply the series of spools and one set of arms to 35 the sleeves, and to remove them, for the substitution of fresh spools and their associated parts when the preceding ones have been exhausted, thus conduced to simplicity and economy.

40 In order to releasably lock the sleeves from movement, there is fitted over the journal bearing of the crank 3'' at the left, a spring cap 15—Figs. 10 and 6, and in said journal under the cap is housed a locking ball 16, which is held down in resilient contact with sockets 17 in the several sleeves. The ball will hold the sleeves against accidental or inadvertent movement, but it 45 will yield to sufficient pressure to permit the 50 sleeves to turn.

I claim:—

1. A manifold attachment for typewriters comprising a rotative member mounted on the platen carriage of the machine parallel 55 with the platen; an arm carried by said member at one end; a member fitted upon the other end of said rotative member; an arm carried by said fitted member; and a manifolding member carried by said fitted member and adapted to be drawn therefrom 60 in successive lengths for engagement by and between said opposing arms.

2. A manifolding attachment for typewriters comprising a rotative member mounted on the platen carriage of the machine, parallel with the platen; an arm carried by said member at one end; an apertured housing fitted upon the other end of said member; an arm carried by said housing; and a manifolding member within the 70 housing and adapted to be drawn therefrom in successive lengths for engagement by and between said opposing arms.

3. A manifolding attachment for typewriters comprising a plurality of independently rotative nested members, mounted on the platen carriage of the machine, parallel with the platen; an arm carried by each of said nested members at one end; a member fitted upon the other end of each of said nested members; an arm carried by each of said fitted members, said arms lying in spaced relation; and a manifolding member carried by each of said fitted members, and adapted to be drawn therefrom in successive 80 lengths, for guidance by the spaced arms and to be engaged by and between said arms and the arms at the opposite end.

4. A manifolding attachment for typewriters comprising a plurality of independently rotative nested members, mounted on the platen carriage of the machine, parallel with the platen; an arm carried by each of said nested members at one end; an apertured housing fitted upon the other end of each of said nested members, said housings being of relatively decreasing diameters; an arm carried by each of said housings and lying in spaced relation to each other; and a manifolding member carried by each of said fitted members, and adapted to be drawn therefrom in successive lengths, for guidance by the spaced arms and to be engaged by and between said arms and the arms at the opposite end.

5. A manifolding attachment for typewriters comprising a plurality of independently rotative nested members mounted on the platen carriage of the machine, parallel with the platen; arms associated with each nested member at each end thereof; a manifolding member carried by and between each pair of arms; a bearing in which said nested members are rotatively mounted; a resilient 110 cap fitted over said bearing; and a ball housed in the bearing under said cap and adapted by the pressure thereof to releasably engage each of said nested members.

In testimony whereof I have signed my 120 name to this specification.

MALCOLM L. COSSITT.
